TYPEWRITING MACHINE

William A. Dobsen, Wethersfield, Conn., assignor
to Underwood Elliott Fisher Company, New
York, N. Y., a corporation of Delaware

Application April 29, 1935, Serial No. 17,403

7 Claims. (Cl. 248—24)

This invention relates to the feet of a typewriter or like machine and deals particularly with a foot structure for a portable typewriter resting on a baseboard of a carrying case.

5 An object of the invention is to provide an efficient noise-deadening cushioning foot, preferably of soft rubber, and which may be easily attached to or removed from the frame of the machine.

10 Another object is a simple, economical connection for removably attaching the foot to the machine.

The base of the foot may have an opening or socket whereby it is adapted to set over a socket-receiving post of a baseboard so as to keep the machine from slipping laterally on said baseboard.

To these and other ends the invention comprises features of construction and combinations 20 of parts within the scope of the following description and the appended claims.

In the accompanying drawing:

Figure 1 is a perspective of separated components of the foot structure.

25 Figure 2 is a cross section, on the trace 2—2 of Figure 3.

Figure 3 is an elevation of the feet as attached to the frame and resting on the baseboard, the latter and one of the feet being shown in section 30 taken on the trace 3—3 of Figure 4.

Figure 4 is a side elevation of the typewriter and shows the baseboard and part of the carrying-case cover in section.

A typewriter 10 has a paper-carriage 11, with 35 a platen 12. The machine stands on a baseboard 13 associated with a removable cover 14, partly shown. A round metal post 24 rises from a metal base-plate 25, which is rigidly connected to the baseboard. Machine feet fit snugly upon 40 such posts. As the foot 19 is pressed down on the post and against the base-plate 25, the rubber is compressed and therefore tends to make the hole 21 smaller and so to exert strong locking or anti-slipping pressure on the post 24.

45 A square or rectangular rubber foot 33 is fastened to the flange 23 of a skeleton-frame 20 of the machine. The molded rubber foot has a shape as shown in full in Figure 1 and sectionally in Figures 2 and 3. The bottom of this foot 50 is hollowed out to give more elasticity to its bottom flange 34. A round hole or socket 21 snugly fitting over the metal post 24 is provided in this foot 33. A square flange 35 at the top of the foot fits in the square eye-hole 36 on the shank 55 23 of the skeleton-frame 20. Two grooves 35a on

opposing sides of the flange 35 of the rubber foot 33, allow a metal foot locking piece or fastener 37 of U-shape, see Figure 1, to be passed into the grooves 35a of the flange 35 after the rubber foot 33 or its flange 35 has been pushed up through the hole 36. In this manner said foot is tightly held to the machine.

A protecting washer 38, with a square hole 39, as shown in Figure 1, is laid between the rubber foot and the eye or supporting-flange 23. The washer with its square hole 39 fits over the flange 35 of the rubber foot.

In assembling the foot to the machine, the washer or cap 38 is laid over the flange of rubber. The foot 33 is inserted into the holed supporting flange or eye 23 on the machine. The locking-piece 37 is inserted through the grooves of the foot, and both legs of the locking-piece enter the holes 40. The latter are cut in the skeleton-frame of the machine, see Figure 1, and the ends of said legs on 37 may be bent over on the outer side of the skeleton-frame, to hold the rubber feet to the machine.

Variations may be resorted to within the scope of the invention, and portions of the invention 25 may be used without others.

Having thus described my invention, I claim:

1. In a portable typewriter, the combination with a typewriting machine, of a baseboard, a shank provided upon the frame of said machine 30 and having an eye, a soft rubber foot having a flange whereby it is buttoned into said eye and having lateral grooves above said eye, said baseboard having a fixed post, said rubber foot having a socket whereby it is removably fitted upon 35 said post and a flat annular shoulder extending beyond said eye beneath the surrounding wall of the shank, and a locking-piece having parts engaging said lateral grooves and overlying the top wall of said shank.

2. In a portable typewriter, the combination with a typewriting machine, of a baseboard, a shank provided upon the frame of said machine and having an eye, a soft rubber foot having a flange whereby it is buttoned into said eye, said baseboard having a fixed post, said rubber foot having a socket whereby it is removably fitted upon 45 said post and a flat annular shoulder extending beyond said eye beneath the surrounding wall of the shank, a metal plate overlying said annular shoulder, and a locking-piece having parts engaging said lateral grooves and overlying the top wall of said shank.

3. In a portable typewriter, the combination 50

- with a typewriting machine, of a baseboard, a shank provided upon the frame of said machine and having an eye, a soft rubber foot having a flange whereby it is buttoned into said eye and having lateral grooves above said eye, said baseboard having a fixed post, said rubber foot having a socket whereby it is removably fitted upon said post, and a flat annular shoulder extending beyond said eye beneath the surrounding wall of the shank, a metal plate overlying said annular shoulder and a part of the side wall of said foot, and a locking-piece having parts engaging said lateral grooves and overlying the top wall of said shank.
4. In a portable typewriter, the combination with a typewriting machine, of a baseboard, a shank provided upon the frame of said machine and having an eye, a soft rubber foot having a flange whereby it is buttoned into said eye and having lateral grooves above said eye, said baseboard having a fixed post, said rubber foot having a socket whereby it is removably fitted upon said post and a flat annular shoulder extending beyond said eye beneath the surrounding wall of the shank, and a U-shaped locking-piece having parts engaging said lateral grooves and overlying the top wall of said shank.
5. In a portable typewriter, the combination with a typewriting machine, of a baseboard, a shank provided upon the frame of said machine and having an eye, a soft rubber foot having a flange whereby it is buttoned into said eye and

having parallel lateral grooves above said eye, said baseboard having a fixed post, said rubber foot having a socket whereby it is removably fitted upon said post and a flat annular shoulder extending beyond said eye beneath the surrounding wall of the shank, and a locking-piece having parts engaging said lateral grooves and overlying the top wall of said shank. 5

6. In a portable typewriting machine or the like having a frame; a shank provided upon the frame and having an eye, a soft rubber foot having a flange whereby it is buttoned into said eye and having lateral grooves above said eye, said rubber foot having an annular shoulder extending beyond said eye beneath the surrounding wall of the shank, and a locking means having parts engaging said lateral grooves and overlying the top wall of said shank. 15

7. In a portable typewriting machine or the like having a frame; a shank provided upon the frame and having an eye, a soft rubber foot having a neck whereby it is buttoned into said eye, said eye and neck being shaped to key the foot against rotation, said neck having an extension above said shank and said extension being laterally grooved above said eye, said foot having a shoulder at the base of said neck extending beyond said eye beneath the surrounding wall of the shank, and a locking means having parts engaging said grooves and overlying the top wall of 25 30 said shank.

WILLIAM A. DOBSON.
